WILLIAM KESTER, OF CHERRYVILLE, PENNSYLVANIA.

Letters Patent No. 80,634, dated August 4, 1868.

IMPROVED MACHINE FOR GRINDING AND POLISHING SCHOOL-SLATES.

The Schedule referred to in these Letters Patent and making part of the same.

TO ALL WHOM IT MAY CONCERN:

Be it known that I, WILLIAM KESTER, of Cherryville, in the county of Northampton, and State of Pennsylvania, have invented a new and improved Machine for Grinding and Polishing School-Slates; and I do hereby declare the following to be a full, clear, and exact description of the same, sufficient to enable those skilled in the art to which my invention appertains to make use of it, reference being had to the accompanying drawings, forming part of this specification, in which—

Figure 1 represents a side elevation, and

Figure 2 a top view of my invention.

Figure 3 is a side view of the car and track detached,

Figure 4 an end view, and

Figure 5 a top view of the same.

In this invention the slates are supported upon a car, which runs under the grinding-stones or wheels, and alternately raises the slates against, or depresses them from the stones. The cars are caused to rise and fall gradually, and yet preserve a perfect level, by means of a series of inclines.

In the drawings, the first three figures represent a machine in which the cars are moved by mechanical devices, and the last two, one in which hand-power is employed for that purpose.

A represents the various parts of the frame which supports the mechanism. B is a circular bed, provided with a double-track railway, b b', around its upper surface, near its rim. Through the centre of this circular bed rises a vertical shaft, C, driven by steam or water-power, and provided with radial arms, c c c c, which extend across over the tracks b b'. A number of vertical shafts, d d d, bearing at their upper end the grinding-stones D D D, are arranged around the circular bed, just inside of the track b b', each driven by belts or gearing from the central shaft, shown at e e. The lower ends of these shafts, below the circular bed, bear in boxes supported upon a pivoted arm, E, or other equivalent device, by which the height of the grinding-stones can be regulated at pleasure.

A car or series of cars, G, runs upon the circular track, travelling round and round upon it, being drawn by the arms c c as the central shaft revolves. The body of these cars supports a horizontal bed or plate, H, upon which, in depressions h h h, rest the slates that are to be ground and polished. The horizontal bed is provided with springs s s, which allow it to yield to pressure from above without losing its level.

Each car runs on four wheels, one pair at each end, and the track b b' is formed of a series of double inclines t t'; the length of each of which is exactly equal to the distance between the axes of the two pairs of car-wheels, so that, while the front end of the car is ascending or descending one incline of the series, the rear end is in the same manner ascending or descending the next succeeding incline of the series, and the car maintains a perfectly horizontal position, although travelling upon an "up" or "down" grade. The inclines are so situated that, as a car approaches a grinding-stone or wheel, it will begin to travel upon the ascending incline t, and will reach the top of it when the middle of the car comes under the middle of the grinding part of the stone; after this it will gradually descend till the slates are entirely removed from the grinding-stone, when it will commence to climb the next incline, in order to present the slates to the next grinding-stone, and so on around the entire circle.

When running on a circular track, the body of the car may be curved to correspond with the circle.

The ascending inclines, t, may, if preferred, be longer than the descending ones, t'. It is only necessary that the inclines should rise equally and descend equally, and that the distance from the top or bottom of one to the corresponding point of the next similar incline should be equal to the distance from the axis of the forward wheels to that of the rear wheels of the car.

The stones D D must be driven with great velocity, while the central shaft C moves slowly. The stones may be driven by gearing from the central shaft, as above described, or from an outside shaft, F, if preferred.

In figs. 4 and 5 the mechanism for driving the cars is omitted, and the double-inclined track t t' is shown

straight. When this form of apparatus is used, the cars are impelled by hand, an operator standing at each end of the track. The operator at K pushes the car through to his companion at L, who turns the slates, and pushes it back. When this arrangement is employed, a track may be laid under each side of the grinding-stone.

Machinery which will give the cars a reciprocating motion may be employed, instead of hand-power, if preferred, but, as the slates must be inserted, turned, and removed by hand, it is presumed that hand-power will be even more economical and convenient for the purpose than other motive-power.

Revolving disks working upon vertical shafts have been for years employed for rubbing down slate. I lay no claim in this connection to the use of such stones or disks, nor to the arrangement of gearing by which they are driven, nor yet to their arrangement around the circular bed; neither do I broadly claim the use of cars running on a circular or straight track, to carry and apply the slates to such grinding-stones.

My claim in this invention is limited entirely to the devices for preserving the level of the cars while they rise towards and recede from the under surface of the grinding-stones, and to the use of the upper or movable plate or bed of the cars.

Having thus described my invention, I may set forth more definitely what I claim as new, and desire to secure by Letters Patent, as follows:

1. The track b b', when composed of the double inclines t t', and used in connection with the cars G G and grinding-stones D D, in the manner and for the purpose specified.
2. The combination of the movable bed H, springs s s; and body of the car G, substantially as and for the purpose specified.

WM. KESTER.
